DISTILLATION OF HYDROCARBON OILS

Robert E. Wilson, Chicago, Ill., assignor to Standard Oil Company, Whiting, Ind., a corporation of Indiana

Application December 31, 1928, Serial No. 329,419

4 Claims. (Cl. 196—58)

The present invention relates to improvements in the art of hydrocarbon oil distillation and is particularly directed to methods for producing a maximum yield of clean pressure-still charging stocks from the heavier portions of crude oil and at moderate cost. By "clean" charging stock is meant a stock which, on cracking by bulk pressure distillation or other cracking operation, does not form any considerable portion of coke.

There are two general methods of producing reasonably clean charging stock from the heavier portions of crude oil. The first is ordinary coking distillation in direct fired batch stills, which gives a high yield of good clean stock, but is expensive to operate, both fuel and labor costs being very high. Practically the whole distillate, except a little gasoline formed by cracking and a little still wax which comes over near the end of the coking operation, can be used in charging stock for bulk pressure distillation processes without giving excessive coke deposit.

The other general method of obtaining charging stocks from the heavier portions of crude oil is a non-cracking distillation effected with the aid of steam or vacuum which assists in carrying over the heavier distillates. While the lighter lubricating distillates thus produced make good charging stock, the very heavy distillates form excessive amounts of coke in cracking. Thus, a skimmed Mid-Continent crude oil from which 40 to 45% of gasoline and kerosene have been recovered may be distilled with steam or vacuum to a 7—8% bottom of very heavy asphalt. Down to about 25% bottom the distillate is a very clean stock. From 25% to 15% the distillate is a fair cracking stock if mixed with lighter stock. The distillate given off below a 15% bottom is a rather dirty cracking stock and needs to be mixed with large quantities of clean charging stock to enable it to be heavily cracked without excessive coke formation. By this process, it is possible to obtain only between 40 and 45% of clean charging stock from Mid-Continent crude oil, as compared with between 50 and 55% by the coking operation.

Again, if Mid-Continent crude oil is distilled with steam down to a low bottom in order to distill off the heavy lubricants, the bottom is practically worthless for most cracking operations, and if distilled to coke in an ordinary coking still the amount charged must be very small, and the expense is excessive.

By the present process, it is possible to obtain from either skimmed crude or heavy reduced crude a maximum yield of clean charging stock

at minimum cost, with the production of certain quantities of coke and gasoline as by-products of value. Furthermore, this process is capable of substantially reducing the amount of coke formed in the coking process heretofore employed, particularly if the oil is first reduced to a relatively small residue, for example about 7 to 10% on the original crude oil.

In carrying out the present invention, the crude oil is subjected to non-cracking distillation to produce a heavy residue, which may be highly viscous or substantially solid at ordinary temperatures. This residue is substantially free from oils in the gas oil range as well as lower boiling oils. This initial distillation may be effected batch-wise or continuously, and wholly or in part with steam or vacuum to prevent substantial cracking. The extent to which the non-cracking distillation is carried may be varied in accordance with the nature of the crude under treatment and the proportions of lubricant products required for market conditions. Thus, in the case of an average Mid-Continent pipe line crude, the non-cracking distillation is suitably carried to such an extent that the residue is not more than about 25% of the crude and in general not less than 7 or 8% in the latter case being of an asphalt-like nature and having a melting point of 80 to 90° F.

The further treatment of this residuum material in accordance with the present invention will be fully understood from the following description in conjunction with the accompanying drawings, in which

Figure 1 is a diagrammatic view of an apparatus suitable for effecting the complete distillation of such residues; and Fig. 2 is an elevational view on a larger scale of a suitable form of distillation chamber.

Referring to the accompanying drawings, a fire and steam still 10, which is the last of a series of continuous stills, is shown as the source of hot petroleum residue. The source may, however, be the flash drum of a pipe still, or other convenient source of hot heavy residue from crude oil, which has preferably been subjected to but little cracking or decomposition. The residue passes by pipe 11 to a pump 12. In case of difficulty in pumping the hot residue, a cooler 13 is provided for the purpose of slightly reducing its temperature to a point at which satisfactory positive pumping may be effected. The pipe 11 is provided with a valve 14 and a valved pipe 15 leads into the pipe 11 between the valve 14 and the pump 12.

The outlet 16 of the pump 12 leads into a suitable pipe still, shown diagrammatically at 17, in which most of the heat is preferably supplied by radiation. The outlet 18 of the coil leads into a plurality of manifolds 18^a, suitably three in number, each of which is connected by valved pipes 19 with one of the chambers 20. The chambers 20 are of substantial dimensions, and are intended to contain the heated oil while distillation to coke takes place. The chambers 20 are preferably vertical and are provided at their upper ends with valved pipes 21 which open to the atmosphere. A valved vapor pipe 22 which communicates with the upper ends of the chambers 20 by valved connections, leads into the base of a suitable fractionating column 23, provided with a vapor outlet 24 which leads into a suitable condenser 25, shown diagrammatically as a water condenser of ordinary type. The condenser feeds 20 into a receiver 26 provided at its bottom with a liquid outlet 27 and at its upper end with a gas outlet 28.

From the top of each chamber 20 a valved pipe 28 extends to a manifold 30 from which valved connections extend to each of the manifolds 18^a, so that the vapors, or a part thereof, formed in one chamber may be passed through another empty chamber thereby preheating it for the reception of residue to be distilled to coke.

30 The chambers 20 are mounted in an elevated position on suitable supporting structures 31 which permit access to their lower ends where the chambers are provided with removable closures 32. The closures 32 are provided with valved pipes 33 for the supply of air or other fluid into the chamber. The pipes 19, associated with each chamber 20, communicate therewith at various levels thereof. The lowest pipe 19 is preferably removably coupled to the pipe 33 so that 40 the heated residue can be supplied into the base of the chamber 20.

The closure 32 may be provided with a small manhole 34, if desired.

The fractionating column 23 may suitably be 45 of the bubble plate type. It is provided with suitable means (not shown) for supplying reflux or condensing vapors to serve as reflux. From the base of the column 23 leads a valved conduit 35, which is provided with a pump 36 and valved 50 branches 37 and 38 connecting with the inlet and outlet, respectively, of the pipe still 17, so that a controlled amount of the heaviest condensate, together with any entrained tar may be returned to the chamber 20. A valved outlet 39 leads from 55 the column 23 at a somewhat elevated point, for example, above the second or third plate, for the purpose of withdrawing clean charging stock.

The operation is as follows: One of the chambers 20 must first be brought to an elevated temperature so that it will not cool the heated residue below cracking temperature. The heating of the chamber may be effected in any suitable manner. For example, it may be heated by passing steam or water through pipes 18 and 18^a into the 65 pipe still 17 and passing the highly superheated steam therewith by pipe 18, the associated manifold 18^a and one or more of the associated pipes 19. It has been found that even better results can be obtained by supplying an oil, such as gas 70 oil, in a similar manner, the vapors therefrom passing by pipe 22 to the condenser 25 where they are condensed.

Another method of preheating the chamber 20 is by combustion therein. In preheating by this 75 method the valve in pipe 21 is opened and those

in pipe 22 and in the connecting pipe 29 are closed. Compressed air is supplied by pipe 31. Any suitable combustible material, for example gas, may be supplied into the chamber and ignited in any suitable manner. Care must be taken to prevent local overheating of the walls, or the formation of an explosive mixture within the chamber. Also, moderately hot products of combustion from any suitable furnace, such as a portable chamber, may be introduced through the pipe 33 or other suitable point of entry such as the manhole 34.

In practice, it is preferred to use the chambers 20 in succession or rotation and to pass the vapors produced in one chamber, or a part thereof, by pipes 29 and 30 into the chamber next to be used and thereby preheat the latter. After passing through the empty chamber, the vapors pass by pipe 22 to the column 23 and condenser 25 associated therewith. No claim is made herein for this method of preheating one chamber by vapors produced in another, or for the structural features whereby such method is effected, the same being described and claimed in the application of Ernest W. Thiele, Serial No. 332,541, filed January 14, 1929, which has matured into Patent No. 1,947,319, Feb. 13, 1934.

The chamber 20 having been brought to a satisfactory temperature, for example 650° F., or preferably higher, petroleum residue, preferably at a high temperature, is supplied by pump 12 to the pipe still 17, through which it is forced at sufficient speed to prevent excessive cracking or coke deposition in the pipes. A little steam may be introduced to speed the flow through part or all of this preheater system, and thus minimize cracking therein, but this is usually not necessary, except for the heaviest residues. In passing through the pipe-still, the temperature of the residue is raised to a satisfactory temperature, for example about 900° F., or such a high temperature that a satisfactory coking temperature is maintained in the chamber 20. It has been found in practice that with heavy residues from Mid-Continent crude the temperature of the entering oil must be above 870° F. to insure the production of a reasonably satisfactory coke without too much volatile matter, while temperatures above 940° F. tend to cause excessive coke formation in the tubes.

The highly heated residuum is admitted into the chamber 20 by means of one or more of the pipes 19, and builds up from the bottom, coking by its contained heat until the chamber is substantially full. It is preferred to supply the heated residuum by the lowest pipe 19 as long as possible and then if it begins to clog, to transfer the stream successively to the next higher pipe 18. This expedient aids materially in the production of denser coke. As indicated above, it is preferred to pass some or all of the vapors from the chamber 20 in which distillation is being conducted, by means of pipes 29, 18^a and 19 into the chamber 20, next to be used. The vapors pass from the latter chamber 20 by pipe 22 into the fractionating column 23. The fractionating column is supplied with reflux or cooling medium in suitable amount to yield an overhead of gasoline or pressure distillate, which is condensed in the condenser 25. The condensate collects in the receiver 26, from which it is drawn off at suitable intervals. The gas and uncondensed vapors escape by pipe 28 and pass to suitable means (not shown) for the recovery of the gasoline therein.

Clean cracking stock is withdrawn by the pipe 39. The reflux from the lowest two or three plates is not sufficiently "clean" and is preferably returned by pipe 35 to either the inlet or outlet of the pipe still 17.

It is preferred to maintain the chambers 20 at approximately atmospheric pressure. Accordingly, the pressure applied by the pump 12 is sufficient to force the residue through the pipe 10 still 17 at the desired rate. The destructive distillation may be effected, however, at moderately super-atmospheric pressures, if desired.

The invention will be more readily understood from the following specific examples of operations on a small commercial scale:

Example I.—Mid-Continent crude is run to a bottom of about 25% by volume in continuous stills and is withdrawn at the rate of about 20 barrels an hour from the last still 10. The 20 residuum is cooled to 720° F. in the cooler 13, since difficulties are experienced in pumping it at higher temperatures. The residuum is pumped through the pipe-still 17, which has eighty-seven tubes of two inches diameter, each approximately fourteen feet long. The outlet temperature is 910° F. The residuum thus preheated is introduced into one of the chambers 20 which has been preheated as described above, and is maintained at substantially atmospheric pressure. 25 The operation is conducted in the manner described above until the chamber 20 is nearly filled with coke. The yields of products expressed in percentages by weight on the crude oil are as follows:

35	Dry gas	1.37
	Gasoline	3.98
	Clean charging stock	19.55
	Coke	3.01

40 The coke is slightly more porous than ordinary tower still coke and can be readily removed by hand tools or other suitable means after the bottom 32 is removed, or through the manhole 34.

Example II.—Mid-Continent crude reduced 45 under substantially non-cracking conditions to about an 8% residue (by volume) is processed in substantially the same way. The yields of products expressed in percentages by weight on the crude oil are as follows:

50	Dry gas	0.58
	Gasoline	1.37
	Clean charging stock	5.65
	Coke	2.25

55 After long continuous runs under the conditions described, the tubes of the pipe-still were substantially free from coke deposit.

It may be noted that the amount of coke produced from the complete distillation of residue 60 in the manner described is substantially less than that produced in tower stills, particularly when the oil is reduced to a low percentage bottom, for example 8%, in still 10.

Although the invention has been described in 65 connection with the details of specific examples, it is not intended that such details shall be regarded as limitative of the scope of the invention, except in so far as included in the accompanying claims.

70 What I regard as new, and desire to secure by Letters Patent is:

1. The method of decomposing heavy hydrocarbon oils substantially free from constituents of the nature of gas oil and lower-boiling constituents to produce a clean condensate charging

stock of the character of gas oil and coke, which comprises heating a confined stream of such oil in an elongated zone of restricted cross-section without the addition thereto of any substantial amount of constituents of the nature of gas oil 5 or lower-boiling oil to a decomposing temperature while causing said stream to move at a sufficiently high speed to avoid substantial deposition of coke in said heating zone, transferring the heated products to an enlarged preheated 10 coking zone without any substantial loss of heat, collecting a body of liquid products of said heating in said enlarged zone without substantial drop in pressure thereon and maintaining said body under low pressure approximating atmospheric 15 at a coking temperature substantially entirely by the heat imparted to said stream of residue in said heating zone for sufficient time to decompose and reduce unvaporized constituents thereof to coke substantially free from liquid 20 ingredients while removing therefrom only vaporous products.

2. The method of decomposing heavy hydrocarbon oils substantially free from constituents of

the nature of gas oil and lower-boiling constituents to produce a clean condensate charging stock of the character of gas oil and coke, which comprises heating a confined stream of such oil in an elongated zone of restricted cross-section without the addition thereto of any substantial 25 amount of constituents of the nature of gas oil or lower-boiling oil to a temperature between 870° and 940° F. while causing said stream to move at a sufficiently high speed to avoid substantial deposition of coke in said heating zone, transferring the heated products to an enlarged preheated 30 coking zone without any substantial loss of heat, collecting a body of liquid products of said heating in said enlarged zone without substantial drop in pressure thereon and maintaining said body under low pressure approximating atmospheric 35 at a coking temperature substantially entirely by the heat imparted to said stream of residue in said heating zone for sufficient time to decompose and reduce unvaporized constituents thereof to coke substantially free from liquid 40 ingredients while removing therefrom only vaporous products.

3. The method of decomposing heavy hydrocarbon oils substantially free from constituents

of the nature of gas oil and lower-boiling constituents to produce a clean condensate charging stock of the character of gas oil and coke, which comprises heating a confined stream of such oil in an elongated zone of restricted cross-section 55 without the addition thereto of any substantial amount of constituents of the nature of gas oil or lower-boiling oil to a decomposing temperature while causing said stream to move at a sufficiently high speed to avoid substantial deposition of coke in said heating zone, transferring the heated products to an enlarged preheated coking zone without any substantial loss of heat, collecting a body of liquid products of said heating in said enlarged zone without substantial drop in pressure thereon and maintaining said body under low pressure approximating atmospheric 60 at a coking temperature substantially entirely by the heat imparted to said stream of residue in said heating zone for sufficient time to decompose and reduce unvaporized constituents thereof to coke substantially free from liquid 65 ingredients while removing therefrom only vaporous products.

70

75

gasoline while permitting gasoline constituents to remain uncondensed, separately removing from the cooling operation a minor proportion of condensed constituents heavier than gas oil and containing entrained tarry matter and a major proportion of condensed gas oil constituents free from entrained tarry matter, the latter constituting a clean gas-oil charging stock, and returning the heavier condensed constituents containing entrained tarry matter to the stream of residuum undergoing heating.

4. The method of decomposing heavy hydro-carbon oils substantially free from constituents of the nature of gas oil and lower-boiling constituents to produce a clean condensate charging stock of the character of gas oil and coke, which comprises heating a confined stream of such oil in an elongated zone of restricted cross-section with the addition of steam but without the addition

thereto of any substantial amount of constituents of the nature of gas oil or lower-boiling oil to a decomposing temperature while causing said stream to move at a sufficiently high speed to avoid substantial deposition of coke in said heating zone, transferring the heated products to an enlarged preheated coking zone without any substantial loss of heat, collecting a body of liquid products of said heating in said enlarged zone without substantial drop in pressure thereon and maintaining said body under low pressure approximating atmospheric at a coking temperature substantially entirely by the heat imparted to said stream of residue in said heating zone for sufficient time to decompose and reduce unvaporized constituents thereof to coke substantially free from liquid ingredients while removing therefrom only vaporous products.

ROBERT E. WILSON.
